UNITED STATES PATENT OFFICE

JOSEPH ERARIO, OF NEW YORK, N. Y.

HEAD GUARD

Application filed July 5, 1928. Serial No. 290,615.

This invention has relation to head gear to be worn by athletes or others engaged in sports, games or contests, and has for its object the provision of a safety hood or helmet 5 of novel construction, embodying features intended and adapted to secure greater safety and comfort to the wearer than the head gears heretofore produced.

The invention consists in the novel construction and combination of features hereinafter described in detail and recited in the claim.

The head gear of my invention is illustrated in the accompanying drawings forming part of this specification in which,

Figure 1 is a side view of the head gear applied to the head of a wearer;

Figure 2 is a rear view;

Figure 3 is a front or face view;

Figure 4 is a fragmentary side view of chin and cheek protecting elements;

Figure 5 is a sectional view through part of the head gear.

The numeral 1 designates generally the body part of the head gear which is in the form of a cap, hood or helmet, comprising the head encircling band 2 with depending cheek guards 3. The upper part of the hood is open as shown at 4 and the side, front and rear portions of the band are connected together by strips 5 of elastic fabric which are stitched together at their intersection forming an open crown which rests upon the head of the wearer. The fore part 6 of the band

30 is adapted to cover the forehead of the wearer to protect the eyebrows and eyelids while the cheek portions 3 reach downwardly at the sides of the face opening below the chin line and terminate in tabs or extensions 7, 7' one 40 of which is provided with a slit 8, and the other with a strap 9 which, when the guard is worn, is passed under the chin of the wearer, through this slit 8, from the inner side, then through the frame of a buckle 8' attached 50 to a strap 8'', which is stitched to and hangs from the cheek section, thence outwardly through a slit 8''' formed in a flap or tab 10 which is stitched to the side of the cheek guard carrying the strap 8'' below the ear 50 openings 11 formed therein. The strap 9 is

then brought back under the chin of the wearer and passes through a loop 8'', stitched to the other cheek guard. Ear openings are provided on both sides of the gear as shown in the drawings, and such flap or tab 10 55 covers and conceals the buckle when the head guard is worn.

The body of the head gear is formed of double thicknesses of suitable leather, the inner layer of which is preferably of thicker 60 and softer stock than the outer layer. These layers are stitched together at various points, and quilted together where desired. The back portion of the headgear is fashioned to fit the individual head and completely overlies the back part of the head.

The ear openings 11 are provided with encircling cushioned protective pads 13. Forwardly of and below the ear guards, the head gear is cushioned or padded as at 14, 15 by 70 the inclusion of suitable padding material between the layers to inclose the jaw and chin for the protection thereof. The front or forehead protective portion 6 is also suitably padded or cushioned.

Between the cheek and forehead sections of the guard a narrow unpadded strip 16 is formed by stitching lines 17, 17 and this strip is perforated as shown at 18 to provide ventilation openings.

The ear pads 13 are formed of separate pieces from the body or head band and are stitched at their margins to the cheek parts, the padded portions extending around the inner parts of the ear openings and being 85 stitched to the inner layer, so as to provide adequate safety and comfort to the wearer.

What I claim as new is:—

A head gear comprising a head band reinforced at the rear side by stitching and padded 90 at the front side, padded sections between the front and rear sides extending downwardly to protect the cheeks and jaw, a perforated area between the front and cheek pads, the band having side openings surrounded by ear pads, depending flaps on the lower sides of the head gear, a strap attached at one end to one flap, a strap guide on the outer side of the same flap, the other flap having an opening therein for the passage of the strap, 100

a strap buckle on the outer side of the other flap, and another flap overlying the buckle and slotted for the passage of the strap from the buckle for holding the same flatly against the buckle while in use and the strap end being threaded through the strap guide.

5 In testimony whereof I affix my signature.
JOSEPH ERARIO.
